[57] CLAIM

The design for a sprinkler controller, substantially as shown.

DESCRIPTION

FIG. 1 is a top perspective view of a sprinkler controller showing our new design.

FIG. 2 is a top plan view thereof.

FIG. 3 is a rear elevation view thereof.

FIG. 4 is a bottom perspective view thereof.

FIG. 5 is a slightly enlarged front perspective view thereof, with the top cover removed.

FIG. 1

FIG. 2

FIG. 3

FIG. 4

FIG. 5
